UNITED STATES PATENT OFFICE

HORACE L. WAISNER, OF ROCKFORD, ILLINOIS, ASSIGNOR, BY MESNE ASSIGNMENTS, TO MECHANICS UNIVERSAL JOINT COMPANY, OF ROCKFORD, ILLINOIS, A CORPORATION OF ILLINOIS

HEAT-TREATING FURNACE

Application filed November 7, 1927. Serial No. 231,639.

This invention relates to heat treating furnaces generally but has more particular reference to one having a mechanical feed and adjustable to accommodate different sizes or 5 kinds of work.

The principal object of the present invention is to provide a furnace for local heat treatment purposes which, while designed to produce and maintain therein a high thermal 10 head for the proper heating of the part or parts of the work requiring such treatment, is so designed that the rest of the work is shielded and remains entirely unaffected by heating.

15 Work requiring local heat treatment, as in the case of trunnions on the arms of a universal joint yoke, presents a rather difficult problem in that where the heating is too sudden there is danger of cracks developing or 20 severe strains being set up, whereas where the heating is slower there is danger of having more of each work piece affected by the heat treatment than is desired as a result of the heat being dissipated from the portion 25 being heated to other portions not intended to be heated. For example, when the trunnions were heat treated by dipping the yokes in molten lead, cracks developed in the arms thereof and many yokes failed to pass inspection 30 for that reason. Hence the necessity for slower heating became evident. The present furnace, as hereinafter described, permits slower heating without danger of heat dissipation from the parts where the heat treatment is desired to those parts which should 35 not be heated.

Another important object of the invention resides in the provision of means in the 40 nature of baffles serving to direct the heat toward the part or parts to be heated, the said baffles being so arranged as to shield the rest of the work.

Still another important object lies in the provision of means whereby the baffles, as 45 well as the mechanical feed, may be quickly and easily adjusted for the handling of different jobs. For example, universal joint yokes, which happen to be the articles under special consideration in the present invention, are made in various sizes for different

sized cars or trucks, and a single furnace as herein constructed may, by slight adjustment, be made to handle any size which may be encountered.

The invention embraces various novel features which will be brought out in the course of the following specification in which reference is made to the accompanying drawings, wherein—

Figure 1 is a side view of my improved heat 60 treating furnace;

Fig. 2 is a central, vertical, longitudinal section through Fig. 1 with the lower part of the frame broken away;

Fig. 3 is an enlarged cross-sectional view 65 on the line 3—3 of Fig. 2;

Fig. 4 is an enlarged fragmentary side elevation of one of the universal joint yokes in its holder, illustrating the novel form of tips employed on the holder;

Fig. 5 is a left hand end view of Fig. 2; and

Fig. 6 is a rather diagrammatic view in section to better illustrate the action of the baffles inside the furnace and to indicate their adjustability as well as the adjustability of the work piece with the mechanical feed, and to 75 illustrate the action of the air blast.

The same reference numerals are used throughout the views to indicate corresponding parts.

The furnace of my invention, as stated above, embodies various features, some of which have special utility where the furnace is used in the heat treating of universal joint yokes. However, it will be understood that these and other features incorporated in the furnace might be used for the general run of local heat treating. The furnace, in other words, might be modified from its present special construction in various minor details to suit the requirements of any particular work which it may be desired to heat treat and, for the most part, it will be evident that in such cases the present invention need not be seriously departed from. No limitation should, therefore, be regarded as imposed on the present invention by reason of any reference herein to its use in the heat treating of 80 universal joint yokes.

Before proceeding to a description of the 100

furnace itself attention may be called to the one example herein illustrated of the kind of heat treating operation which the same is capable of performing, namely, the heat treatment of the trunnions 8 on the arms 9 of universal joint yokes 10. When these yokes were dipped in molten lead for the heat treatment of the trunnions, the arms 9 were frequently found to have cracks developed there-in as a result of the too sudden heating. According to the present invention, care is taken to avoid the heating of the arms 9 and to confine the heating to the trunnions; the arms 9 and the rest of the body part of the yoke 15 being cooled so as not to be affected by the heating of the trunnions by reason of any conduction from the trunnions through the arms. The arms are shielded during the heating of the trunnions and an air blast is played 20 onto the body of the yoke to keep the temperature thereof as low as possible. The yokes are forged and then practically completely machined, only the trunnions being left slightly oversize. They are then heated 25 at suitable temperatures following which they are quenched and then tempered to relieve any strains which might exist therein. After this, the trunnions are ground to size and the yokes are ready for use. The aim in this heat 30 treatment, according to the present invention, is to avoid too sudden heating and any other conditions which might tend to develop cracks or abnormal strains. Such slight strains as are set up as a result of this heat 35 treatment are easily relieved in the tempering operation which immediately follows.

The shell or casing 11 of the furnace is supported on a frame or base 12, the latter affording a place for the support of the driving motor 13, variable speed gear box 14, and reduction gear casing 15, furnishing the power for the driving of the mechanical feed for feeding the work through the furnace at the desired speed. Chain driving connections for the chain conveyor 16 are indicated at 15^a and 15^b. The variable speed gearing in the box 14 permits of whatever variation in the rate of travel of the conveyor may be deemed advisable for different jobs. 45 The work is placed in the holders 17 by an attendant standing at the front of the furnace (the left hand end as seen in Fig. 1) and is removed with tongs by an attendant standing at the back of the machine who also takes care of the quenching thereof. The work is carried on the holders 17 through an elongated firebox or heating chamber 18 extending lengthwise of the furnace and during its travel is subjected, on 50 both sides, to the action of the gas flames from the burners or nozzles 19 mounted in the opposite side walls of the furnace. The yokes travel in the manner shown most clearly in Fig. 2 with the trunnions disposed in 55 the direction of travel, thus presenting the

trunnions broadside to the action of the burners. The flames from the burners, as shown in Fig. 6, are deflected upwardly on the inclined tops of baffles 20 and are thus caused to envelop the trunnions, the spent gases being allowed to escape through flue openings 21 provided directly over the path of travel of the yokes in the top of the heating chamber. The baffles 20 extend lengthwise of the heating chamber 18 and are disposed at opposite sides thereof, as shown, so that the yokes travel therebetween in passing through the furnace. The baffles, in addition to directing the flames properly onto the work also serve to shield the latter in a manner believed to be self-evident from the diagrammatic showing in Fig. 6. The heating is, therefore, confined almost entirely to the trunnions. In addition to minimizing the heating of the bodies of the yokes I also provide an air blast manifold 22 which delivers air jets from beneath into the heating chamber to play onto the yokes so that the bodies and arms thereof are kept below their lower critical temperatures and therefore are not hardened upon quenching. The air discharged from the manifold 22 is directed in a line toward the flues 21, thus aiding the draft for the burners 19. The products of combustion are entrained with the air as it passes upwardly through the flues.

The furnace is lined with firebrick 23, the flue openings 21 being formed therein in the manner indicated. Fire clay is also used in the construction of the inside of the furnace, as indicated at 24. The gas nozzles 19 are introduced through openings in the walls of the furnace and are suitably provided with special tips 25 which give good flame distribution. The nozzles are threaded at their outer ends, as at 26, for reception in the openings 27 provided in evenly spaced relation along the inside wall of each of the manifolds 28. The outside wall of each manifold is provided by a back plate 29 removably fixed thereon so that access may be had to the nozzles, the latter being arranged to be screwed into and out of place by use of a screw driver, the slots for which appear in the drawing. The nozzles are removed from time to time for inspection and cleaning or replacement of the tips; hence the provision of the removable back plates is of considerable advantage. Good gas distribution to all of the nozzles is also insured by having the gas supply pipes 30 delivering into the manifolds at points spaced evenly longitudinally of the manifolds. The condition does not arise where some of the nozzles, as for example at the ends of the manifolds, are starved more or less. The uniform gas distribution, of course, makes for uniform heating which is of great importance. The valves 31 are provided to regulate the flow of gas in 130

order that the desired temperature may be maintained in the furnace. The three pipes 30 for each manifold are suitably connected in common to an air and gas mixer in order to produce Bunsen flames at the burners 19.

Equal distribution of the air discharged from the manifold 22 is secured in a somewhat similar manner as in the distribution of the gas. The manifold 22 has a series of evenly spaced jet openings 32 in the wall thereof along one side. A pipe 33 is sealed in one end of the manifold 22 and extends therein substantially the full length thereof and has a number of relatively widely spaced openings 34 provided in the wall thereof along one side diametrically opposite from the openings 32 in the wall of the manifold 22. The inner end of the pipe 22 is suitably closed to insure discharge of the air at the openings 34 into the manifold 22. Air is supplied to the pipe 33 through a hose connection 35 communicating with the outer end of the pipe. Uniform distribution is secured in the discharge of the air through the openings 32 since the discharge is in no way confined to the immediate locality of the openings 34 in the pipe 33. The discharge of the air is, furthermore, fairly gentle and not with as much force as might be implied by the use of the expression "air blast". Only sufficient air is supplied to insure the keeping cool of the bodies and arms of the yokes.

The conveyor 16 operates over a drive sprocket 36 and an idler sprocket 37, the latter being adjustable with relation to the former in order to take up slack in the conveyor. The brackets 38 and 39, which provide mountings for the sprockets 36 and 37, are carried on the ends of guide rails 40. Angle iron strips 41 fixed on the upper ends of the rails 40 provide guideways between the inturned flanges thereof and the upper edges of the guide rails 40, as indicated at 42, for the sliding reception of shield plates 43, one of which is provided for each of the work holders 17 and extends substantially from opposite sides of the conveyor chain to be received at its lateral edges in the guideways 42. The plates 43 are called shield plates for the reason that they have openings 44 therein at only a central point to permit the air blast to reach only the bodies and arms of the yokes and not the trunnions. The plates 43, however, serve also by their travel through the guideways 42 to keep the work holders 17 moving along a straight and even path of travel. Thus, the exposure of the trunnions in the heating chamber is uniform from end to end thereof. The amount of exposure desired obviously depends on the size of the trunnions and since there is an appreciable variation in the size of trunnions for different sized

universal joint yokes, I have provided means for adjusting the elevation of the guide rails 40. The adjustment of the latter will, of course, result in the adjustment of the conveyor as a unit and all of the work holders will consequently be adjusted to an equal degree to vary the amount of exposure of all of the work pieces in the heating chamber to precisely the same degree. It will be observed that the guide rails 40 have bolts 45 extending through slots 46 in lugs 47 provided on the members of the frame 12. These bolts serve to guide the rails 40 for up and down movement and prevent end-wise displacement thereof. A pair of cams 48 is provided on each of two shafts 49 and 50. A lever 51 is fixed to the shaft 49 to permit the turning of the cams to secure the desired elevation of the guide rails, the two shafts 49 and 50 being interconnected by a link 52 and levers 53 and 54 so that the turning of one shaft causes the turning of the other. A ratchet gear 55 fixed on the shaft 49 has a pawl 56 engaging the same to serve in holding the cams 48 in any desired state of adjustment. The change in exposure of each work piece resulting from the adjustment of the guide rails is indicated in dotted lines in the diagram of Fig. 6 where the yoke 10 is shown in full and dotted lines.

When the elevation of the conveyor is changed some slight adjustment of the baffles 20 is usually necessitated, as indicated in dotted lines in Fig. 6. The baffles, it will be observed, have the body portions thereof made of firebrick mounted on metallic base pieces 57 and held in place by plates 58 and angle irons 59. The adjustment of the baffles may be made by the operation of rods 60 attached to the base pieces 57 and extending outwardly through tubular guides 61 for connection with levers 62 pivoted on the outside of the casing 11. The levers 62 engage ratchet sectors 63 to hold the same in any position of adjustment. Two levers are preferably provided for each baffle, one at each end thereof (see Fig. 1). Thus, the same amount of adjustment may easily be made at both ends of the baffles and the baffles will, therefore, be kept substantially parallel.

The base pieces 57 of the baffles are suitably cast to provide longitudinally extending water-circulating passages 77 and 78 in communication with one another at one end thereof, as indicated at 79, and having inlet and outlet hose connections 80 and 81 communicating therewith at the other end. The inlet hoses 80 are suitably interconnected by a T fitting and the outlet hoses 81 likewise in order to simplify the water cooling system. The flexibility of the hose connections obviously permits of the adjustment of the baffles toward and away from one another, as

above described. The baffles, by reason of the water cooling, are protected from overheating under the direct play of the gas flames thereon.

5 The inlet and outlet ends of the furnace are closed by end plates 66 and 67, respectively, which have openings, as indicated at 68, for the water hose connections and central openings 69 to permit the passage there-through of the work holders 17 with the yokes in place thereon. Bolts 70 serve to fasten the plates 66 and 67 in place on the ends of the casing 11. When the furnace is being adjusted to operate on a run of larger 10 or smaller yokes, the end plates 66 and 67 are removed and other end plates substituted having the proper sized openings 69 therein. The thought is to avoid, as much as possible, any indrafts of cold air or escape of heat 15 through the openings at the opposite ends of the furnace. The bolt holes in the plates 66 and 67 are provided slightly elongated 20 so that the plates may be set to give the work the proper clearance in entering and leaving 25 the furnace.

The tops of the baffles 20, as clearly appears in Figs. 3 and 6, are conformed to provide flat ledges 82 at the lower end of the inclined portions 83. Any dirt or dust during 30 the operation of the furnace will tend to collect on these ledges. The end plates 66 and 67 have sight openings 84 provided therein in line with the ledges through which the accumulation of dust and dirt can be observed 35 and through which an air nozzle may be entered to permit the same to be cleaned out. Covers 85, swingable out of the way, serve normally to close the sight openings. Where the baffles are brought together as, for example, as shown in dotted lines, in Fig. 6, there is a likelihood of some dirt and dust dropping down from the ledges 82 onto secondary ledges 82' provided by the angle irons 59. When that occurs the air nozzle may be 40 introduced through the openings 68 in the end plates 66 and 67 (see Fig. 5) to clean out such dust and dirt. Obviously, keeping the furnace clean makes for generally more efficient operation.

50 In Fig. 4, I have illustrated tips 71 which are arranged to be mounted on the arms 72 of the work holders 17 to engage and support the yokes just beneath the trunnions thereof in the manner clearly shown in Figs. 55 2-4. The tips 71 are slightly relieved at the ends thereof, as indicated at 73 in Fig. 3, to form seats for the trunnions for the better holding thereof. The free ends of the tips are also offset, as indicated at 74, to provide 60 flat portions to rest in engagement with the sides of the yokes beneath the trunnions. The end portions of the tips are of considerably reduced cross section, as most clearly appears in Fig. 4, for the purpose of minimizing the 65 heat conduction from the trunnions to the

arms of the work holders. A pair of openings 75 is provided in each half of the length of the tip to permit the fastening of the tips in either of two positions as by means of rivets 76. Thus, after a new set of tips has been in service for a certain length of time and the ends thereof which have been exposed to the heat in the furnace have burned off more or less, the tips may be removed, reversed end for end, and fastened in place 75 again so that the other ends thereof may be used. An appreciable saving in maintenance expense is thereby derived.

I claim:

1. A heat treating furnace comprising, in combination, a casing providing an elongated heating chamber therein, an endless conveyor operating through said casing having means thereon for holding work to feed a portion of the same through the casing, means for directing flames onto the work from both sides as the same is fed through the casing, means so disposed as to shield a part of the work on both sides thereof from the action of said flames, comprising baffles arranged to direct the flame toward the part or parts of the work to be heat treated while at the same time serving to shield the rest of the work.

2. The combination as set forth in claim 1 wherein the last mentioned means comprises baffles arranged to direct the flames upwardly toward the part or parts of the work to be heat treated, the said baffles being adjustable horizontally toward and away from one another to suit the work being handled and wherein the endless conveyor is adjustable vertically to vary the amount of exposure of the work in said casing above said baffles.

3. In a furnace of the character described, a casing providing an elongated heating chamber therein, an endless conveyor operating lengthwise of said chamber for feeding work therethrough to be subjected to heating therein, the said conveyor extending beyond the input and output ends of said chamber at the ends of said casing, means on said conveyor for holding the work pieces so that only a part of each is exposed for heating in said chamber, a frame supporting the casing, means carried by the frame and extending beyond the ends of the casing for supporting the conveyor, and means for adjusting the last mentioned means relative to the frame whereby to adjust the conveyor in relation to the heating chamber so as to change the amount of exposure of the work pieces therein.

4. A furnace as set forth in claim 3 including air blast means disposed lengthwise with respect to the conveyor for delivering air onto the unexposed parts of the work pieces to keep the same cool, said air blast means being adjustable with the conveyor whereby to maintain a predetermined relationship there-

with regardless of adjustment of the conveyor with its support.

5. A furnace of the character described comprising a casing providing an elongated heating chamber therein, a support for the casing, an endless chain conveyor beneath said casing operating lengthwise of the heating chamber, work holders mounted on said conveyor and extending up into the heating chamber while traveling along the upper flight of the chain conveyor, said work holders being arranged to support work pieces so that a part of each is exposed in the heating chamber, a guide on said support for the upper flight of the chain conveyor to insure the same amount of exposure of each work piece throughout the travel thereof in the heating chamber, and means for adjusting the elevation of the guide with relation to the support whereby to vary the amount of exposure of the work pieces in the heating chamber.

6. A furnace as set forth in claim 5 wherein the last mentioned means comprises a pair of cam shafts mounted on the support and having the guide resting on the cams thereof, the guide being held against endwise movement with relation to the support but guided for vertical movement with respect thereto, a hand lever attached to one of said shafts for turning the same, means extending between the shafts to transmit rotation from one to the other, and means for holding said shafts in adjusted position.

7. In a furnace of the character described, an air blast device comprising an air supply pipe, and a tubular manifold extending substantially the length of the pipe and having the latter sealed therein, the pipe having several relatively large air discharge openings in the wall thereof along one side and having the inner end thereof closed and the outer end thereof arranged for connection with an air supply means, and said manifold having a plurality of closely spaced relatively small air jet openings in the wall thereof along one side, the last mentioned openings being disposed in diametrically opposed relation to the first mentioned openings substantially as and for the purpose described.

8. In a furnace of the character described, the combination of an elongated chamber, means operating lengthwise of the chamber for feeding work therethrough to be subjected to heating therein, only a certain part of each work piece being exposed in said chamber, means in said chamber for heating the exposed parts, and means disposed longitudinally of the path of movement of the work pieces for delivering an air blast on the work pieces during the travel thereof through the heating chamber to keep cool the unexposed parts of the work pieces.

9. In a furnace of the character described, a casing providing an elongated heating

chamber therein, a work carrier operating lengthwise of the heating chamber, burners at opposite sides of the heating chamber, arranged to have the flames thereof played onto the opposite sides of the work as it passes through the chamber, baffles at opposite sides of the chamber between which the work is arranged to pass, said baffles serving to direct the flames against the part of the work to be heated and to shield the rest thereof, and means for delivering an air blast between the baffles against the unexposed part of the work, said heating chamber being closed on top over the baffles to confine the flames of the burners to the exposed part of the work but being provided with a flue opening in line with the air blast means so that the air discharged from the latter escapes through the flue opening and entrains the products of combustion from the burners.

10. In a furnace of the character described, a casing providing an elongated heating chamber therein, a work carrier operating lengthwise of the heating chamber, burners at opposite sides of the heating chamber, arranged to have the flames thereof played onto the opposite sides of the work as it passes through the chamber, baffles at opposite sides of the chamber between which the work is arranged to pass, said baffles serving to direct the flames against the part of the work to be heated and to shield the rest thereof, and means for delivering an air blast between the baffles against the unexposed part of the work, said burners being disposed in a plane below the exposed part of the work to be heated and said baffles being upwardly inclined from the burners toward the work to deflect the flames upwardly so that they play properly onto the exposed part of the work to be heated and being directed away from the rest of the work that is not to be heated, said heating chamber having a flue opening in the top midway between the burners and directly over the work to conduct the products of combustion away from the burners.

11. In a furnace of the character described, a casing providing an elongated heating chamber therein, a work carrier operating lengthwise of the heating chamber, burners at opposite sides of the heating chamber, arranged to have the flames thereof played onto the opposite sides of the work as it passes through the chamber, baffles at opposite sides of the chamber between which the work is arranged to pass, said baffles serving to direct the flames against the part of the work to be heated and to shield the rest thereof, means for delivering an air blast between the baffles against the unexposed part of the work, and means disposed between the air blast means and the work to shield a part of the work from the air blast so that the cooling air is played only on the part thereof in-

tended to be cooled and not on the part being heat treated.

12. In a heat treating furnace comprising a conveyor having work holding devices thereon for holding work pieces in the heating zone of the furnace for heat-treatment, the work pieces having only that part thereof exposed which it is desired to heat treat, tips on the work holders for supporting the work pieces, each of said tips having one part thereof arranged to be fastened on the work holder and having the other part thereof arranged to support the work piece, only the latter part being exposed in the heating zone of the furnace in operation, said tips being reversible end for end and arranged to be held in either position on the work holder for the purpose described.

13. A heat treating furnace comprising, 20 in combination, a casing providing an elongated heating chamber, a mechanical conveyor operating through said casing for feeding work therethrough, means for directing flames toward the work, an inclined baffle for deflecting the flames onto the part or parts 25 of the work to be heat treated, there being a ledge whereon dust and dirt from within the casing and off the baffle is arranged to collect, the casing having openings in the end 30 walls thereof in line with said ledge permitting inspection of the inside of said casing and the introduction whereby to clean out accumulated dust and dirt from said ledge, and means normally closing said open- 35 ings.

14. A heat treating furnace comprising, in combination, a casing providing an elongated heating chamber therein, a mechanical conveyor for feeding work through said casing, means in the opposite side walls of said casing for directing flames onto the opposite sides of the work, a pair of baffles at opposite sides of said conveyor in said casing for deflecting the flames toward the part or parts 40 of the work to be heat treated, and means for adjusting each of said baffles comprising rods attached thereto and extending outwardly through the side walls of said casing, levers pivoted on the outside walls of said 45 casing and connected to said rods to reciprocate the latter, and means for detachably holding the levers in adjusted position.

In witness of the foregoing I affix my signature.

HORACE L. WAISNER.
